FOLDING OR SLIDING CLOTHES POLE

James Clink, East Cleveland, Ohio

Application March 31, 1939, Serial No. 265,226

1 Claim. (Cl. 248—353)

The present invention relates to clothes poles and more particularly to collapsible or folding clothes poles.

The object of the present invention is the provision of a novel, simple clothes pole comprising a plurality of pole sections hinged or slidably connected together and so constructed that the different sections of the pole are rigidly connected together when the pole is extended, but can be readily folded when not in use.

The present invention resides in certain details of construction, combinations and arrangements of parts and further objects and advantages thereof will be apparent to those skilled in the art to which the invention relates from the following description of the preferred embodiments thereof described with reference to the accompanying drawing forming a part of this specification, in which similar reference characters designate corresponding parts and in which—

Fig. 1 is a side elevational view of a clothes pole embodying the present invention.

Fig. 2 is a view similar to Fig. 1, but with portions broken away, showing the clothes pole partly folded.

Fig. 3 is a view similar to Fig. 1, but showing a modified construction.

Fig. 4 is a view similar to Fig. 3 showing the clothes pole in folded condition.

Fig. 5 is a view similar to Fig. 1, but showing a further modified construction.

Fig. 6 is a view similar to Fig. 5, but showing the parts in a different position.

Fig. 7 is a side view of the clothes pole shown in Fig. 5, looking from the right.

Fig. 8 is a view similar to Fig. 6, but showing the clothes pole in folded condition, and

Fig. 9 is a sectional view on the line 9—9 of Fig. 7.

Referring to the drawing, the clothes pole shown in Figs. 1 and 2 and designated generally by the reference character A, comprises upper and lower pole sections 10 and 11, respectively, connected together by a hinge 13 comprising upper and lower tongues 14 and 15, respectively, of unequal length connected together by a pintle pin 16. The pole sections 10 and 11, as shown, are square and made of wood, however, they may be either round or square, etc., and may be made of light weight metal, etc. The pole sections 10 and 11 may be of any convenient length. The upper end of the upper section 10 is provided with a wire loop 12 for the reception of a clothes line (not shown) and the lower end of the lower

section is preferably provided with a spike or made pointed to prevent the same from slipping. The upper and lower tongues 14 and 15 of the hinge 13 are located in cut-out portions provided in the sides of the upper and lower pole sections 10 and 11 so as to be flush with the outside of the pole, and are secured thereto in any convenient manner as by the screws 17. The adjacent or abutting ends 18 and 19 of the pole sections 10 and 11 are mitered and the construction is such that when the clothes pole is extended, the pole sections are coaxial and the adjacent ends 18 and 19 contact each other diagonally of the longitudinal axis of the clothes pole and at a considerable distance below the pintle pin of the hinge.

In the embodiment of the invention shown in Figs. 1 and 2, the two pole sections 10 and 11 of the clothes pole, when extended, are held in the aligned position by a tubular sleeve 20 slidably thereon and adapted to be retained in a position to enclose the adjacent ends of the pole sections 10 and 11 by a resilient detent 21 fixed in an aperture 22 in the lower pole section 11, one end of which detent is adapted to normally project through an aperture 23 in the sleeve member 20. When it is desired to fold the clothes pole the detent 21 is depressed and the sleeve 20 lowered until it engages a stop, that is, until it reaches the position shown in Fig. 2. Thereafter, the upper pole section 10 can be folded by rotating the same about the pintle pin 16 until both pole sections are parallel or lie side by side. The sleeve 20 is preferably provided with a second slot 25 through which the detent 21 projects when the sleeve 20 is in its lower position.

Figs. 3 and 4 show a clothes pole embodying the present invention but of modified construction. The clothes pole shown in these figures comprises upper and lower pole sections 30 and 31 connected together by a hinge 32 similar in construction to the hinge shown in Fig. 1. The adjacent ends 33 and 34 of the pole sections 30 and 31, respectively, are at right angles to the length of the pole and when the pole is extended, they abut each other. The principal difference between the clothes pole shown in Figs. 3 and 4 and the clothes pole shown in Figs. 1 and 2 is in the construction of the sleeve 35 which holds the pole in extended position. The sleeve member 35 in the present instance is slidably supported on the upper pole section 30 and when the pole is extended, the sleeve member 35 remains in its down position due to the force of gravity. The right-hand side of the lower half of the

sleeve member 35, as viewed in Fig. 3, is cut away, which allows the sleeve member to project below the pintle pin of the hinge 32, which in the present instance is located at the break between the two pole sections, as distinguished from the construction shown in Fig. 1 where the pintle pin 16 is located above the break between the two pole sections, thus eliminating the necessity of the sleeve member 20 extending past the pintle pin. When the clothes pole shown in Fig. 3 is extended, it is held in extended position by the engagement of a plurality of pins 36, one on either side of the lower pole section, which pins 36 engage within suitable slots formed in the lower ends of the sleeve member 35. When it is desired to fold the pole, the sleeve member 35 is raised and the upper pole section 30 rotated until it lies parallel with the lower pole section 31, which is the position shown in Fig. 4. A stop 37 fixed to the upper pole section 30 above the sleeve member 33 limits the movement of the sleeve member towards the upper end of the pole. This prevents the sleeve member 33 from dropping to the end of the pole when the upper pole section 30 is rotated in the position shown in Fig. 4.

A further modification of the clothes pole shown in Figs. 1 and 2 is shown in Figs. 5 to 9, inclusive. As shown in these figures, the adjacent ends of the upper and lower pole sections 40 and 41 are telescoped within a sleeve member 42 fixed to the lower pole section 41 as by bolts 43. The clothes pole is folded by raising the upper pole section 40 so that the lower end thereof clears the upper end of the sleeve member 42. When the upper pole section is in this position, see Fig. 6, it is held in assembled relation with the lower pole section 41 by a U-shaped member 44 having inturned flanges 45 which engage in slots 46 formed in the sides of the upper pole 40 section 40. The member 44 is hinged to the up-

per end of the sleeve member 42. After the upper pole section 40 has been raised to the position shown in Fig. 6, it can be readily folded over against the lower pole section 41, as shown in Fig. 8. A pin 49 fixed in the lower end of the upper pole section 40 and extending through a slot 50 in the member 44 limits the movement of the upper pole section 40 relative to the member 44. The construction is such that the various parts of the clothes pole are always maintained in assembled relation.

From the foregoing description of the preferred embodiment of the present invention, it will be apparent that the objects of the invention hereinafter enumerated have been accomplished and that a simple, reliable and novel folding clothes pole has been provided. While the preferred embodiments of the invention have been described with considerable detail, I do not wish to be limited to the construction shown which may be varied within the scope of this invention and it is my intention to cover hereby all adaptations, modifications and variations thereof that come within the practice of those skilled in the art to which the invention relates and I particularly point out and claim as my invention the following:

An extendible clothes pole comprising a plurality of pole sections adapted to be axially aligned, a sleeve member fixed to one of said pole sections and adapted to receive the end of the other of said pole sections, a member slidably connected to the pole section other than the pole section to which said sleeve member is connected, means for limiting the relative movement between said member and the pole section to which it is slidably connected, and means for pivotally connecting said member to said sleeve member.

JAMES CLINK.
